UNITED STATES PATENT OFFICE.

JAMES NISBET, OF GLASGOW, SCOTLAND.

MERCURY-VAPOR LAMP.

Application filed September 21, 1925, Serial No. 57,757, and in Great Britain September 11, 1924.

My invention relates to improvements in mercury vapor lamps, and has for its objects to so construct these as to obtain a much greater brilliancy and illumination for projecting pictures by means of transparencies or of opaque objects by reflection onto a screen, and for emitting remedial rays for medical or other scientific purposes.

According to this invention I provide a 10 mercury vapor lamp comprising an outer shell and an inner shell arranged to form a hermetically sealed mercury vapor space therebetween, one of said shells being provided at both ends with a pocket communicating with said vapor space and arranged to contain mercury and an electrode in each of said pockets to cause electrical circuits through the mercury at both ends and throughout said sealed chamber.

20 The two electrodes at opposite ends of the lamp dip into the mercury and thus, when the current is switched on, complete the circuit or circuits vaporizing the mercury, and filling the entire vacuum or gas filled chamber with luminous mercury vapor.

When the current is switched off the vapor is condensed ready for the next operation.

The vapor lamp is here shown as parabolic, but may be of any suitable shape and its back is silvered to act as a reflector or mirror.

The vacuum chamber walls of the body of the lamp may be composed of quartz glass or other suitably annealed glass adapted to stand the temperature. Where the greenish tint of the mercury vapor is desired to be eliminated, certain chemicals, such as cadmium and such like may be added to the mercury in the vacuum chamber. Likewise to prevent the mercury or vapor adhering to the electrodes or to the walls of the vacuum chamber, zirconia or silica, or other oxides of metal and gas, such as carbonic acid gas, may also be added in order to counteract any little air or oxygen which might gain access at any time to the vacuum chamber.

In order that my invention may be clearly understood and readily carried into effect,

I have hereunto appended sheets of drawings, of which:

Figure 1 is a central sectional view of a mercury vapor lamp constructed in accordance with my invention.

Figure 2 is an elevation of the same. 55

Figure 3 is a sectional view through the line 3—3 of Figure 1.

Figure 4 is an end elevation of the smaller end of the lamp.

Figure 5 is a sectional view of a modified 60 form of my lamp.

Figure 6 is a sectional view of a double shelled saucer-shaped lamp constructed in accordance with another modified form of my invention. 65

Figure 7 is a sectional view of a double shelled conical-shaped lamp constructed in accordance with another modification of my invention.

Figure 8 is an elevation of a spiral single-tube lamp constructed in accordance with another modification of my invention. 70

Figure 9 is a sectional view of a double shelled hemispherical lamp constructed in accordance with another modification of my invention. 75

Figure 10 is a diagram showing a battery of single walled tubular lamps for surrounding the lens P, when reflecting an opaque object back through the lens P onto a screen. 80

Figure 11 is a diagrammatic elevation corresponding to Figure 10.

Figure 12 is a sectional view of a double shelled cylindrical lamp, forming another modification of my invention. 85

Figure 13 is a diagrammatic section of a double-shelled lamp constructed in accordance with another modification of my invention and having double walls in one piece (continuous) but open at neck and mouth, 90 and in which combined platinum terminals and electrodes are inserted while the glass is plastic. In this form the outer, larger wall or shell may be made separately from the inner wall or shell and the two hot shells may be welded to each other at the two mouth ends and two neck ends respectively. 95

Figure 14 is an elevation of a detachable

filler tube, with two stop-cocks and filler mouth for the insertion of mercury without danger of air getting into the tube of the lamp, and may be also used for exhausting 5 sealed space to give a vacuum.

Figure 15 is a side view, partly in section, of a modified form of tubular electrode.

Figure 16 is a section taken on the line 15—15 of Figure 1.

- 10 Referring especially to Figures 1, 2, 3, 4 and 16, the lamp comprises a shell A of quartz glass or of any suitable material which is silverized on its exterior surface to act as a reflector and which has contained 15 therein another shell B consisting of quartz glass or of any other transparent heat resisting material, and held concentric with the outer shell A by means of circular spacing pieces or gaskets C. These circular 20 spacing pieces or gaskets are of renewable heat resisting materials and may or may not be nonconductors of electricity and act as renewable seals at each end of the lamp to keep the vacuum or gas space X between 25 the chambers or shells A and B gas-tight, at the larger and smaller ends. Caps J are screwed onto each end of an outer casing which is arranged on the outer shell A and compresses the spacing pieces or gaskets C 30 between the shells A and B. The spacing pieces or gaskets C and the glass at both ends of the lamp are slightly tapered thus ensuring, with the addition of a film of cement or plaster of Paris, an air-tight and 35 changeable joint. The inner faces of the gaskets C are provided with mica discs or washers E³ and tungsten copper discs or washers E⁴ to prevent the electrical arcing 40 affecting the gaskets C and from polarizing or neutralizing the electrodes or from cracking 45 the "glass shells".

The outer shell A is enlarged at each end to form a circular pocket D, into each of which pockets D there is inserted an electrode ring E electrically connected to terminals F at the exterior of the lamp. For 45 filling or charging the pockets D with the requisite amount of mercury L and for charging and exhausting chamber space or 50 working it at atmospheric pressure, inlets G are formed in tubes A², the ends of which are extended a little so that they may be used as trunnions for supporting the lamp. The tubes A² are provided on opposite sides 55 of the shell A, the opening and closing of each of said inlets being controlled by a stop-cock or valve H.

To enable the shell A to be heated before the main current is turned on and prevent 60 fracturing of the shell I provide suitable electric heating coils which are arranged around the tubes A².

In order to supply mercury to the cups D, a glass tube G¹ is provided with two stop-cocks H¹ and H² and a funnel mouth G³,

(see Figures 1 and 14) which is detachably secured to one or other of the inlets G and may also be attached to any of the tubulous terminals of any of the lamp forms by suitable means. The stop-cocks H² and auxiliary tube, (Figure 14) are also used for exhausting mercury, air or gases from the interspace X before the latter is recharged with fresh mercury or gases and for working the vapor space at atmospheric pressure, 70 the said gases being blown through one stop-cock and out at the other, and both stop-cocks being closed when the air or gas has thus been expelled or exhausted and favorable vacuum formed; or two stop-cocks 80 opened for working vapor space at atmospheric pressure when wanted in space X. The stem M¹ of a suitable initial, or auxiliary, electric heating, illuminating and tinting lamp M is adjustably arranged in 85 a bushing O provided at the small end of the shell B so as to protect the shell B and a globular condenser V (referred to hereafter) from fracture by the sudden great heat caused when the electric current 90 or currents are turned on to main circuit of the lamp. Air or liquid cooling circulation into the interior Z of the lamp shell B, Figure 1, and on all double walled lamps, is arranged to take place through passages N 95 in the bushing O, and passages O¹, Figures 1 and 16, and the circulation of cooling liquid or air for the outer or inner side of the shell A, or of the enclosed space can also be arranged if required. The globular 100 hollow quartz condenser V is of the thermosiphon type, cooled by circulating cooling liquid and this or other condenser can be used so as to give cinema projections with convergent beams of light. 105

The tubular electrode, for providing an auxiliary supply of mercury vapor, comprises according to a modification of my invention, as shown in detail in Figure 15, a frame of two substantially semicircular 110 tubes E¹⁰ which are connected at their bottom ends by a T-piece E⁵ or elbows. An elbow E⁶ is secured to the other end of the limb E¹⁰ and to a tube E⁷, projecting through the asbestos gasket C¹⁵ and a tungsten copper disc E¹⁴ and mica washer E¹³ provided on the inner face of said gasket. A stop-cock H⁵ or valve is provided in the tube E⁷ and is connected to an elbow-piece E⁸. A tube E⁹ is connected to the T-piece 115 E⁵ and extends through the disc E¹⁴, washer E¹³ and gasket C¹⁵, said tube also being furnished with a stop-cock or valve H⁴. Terminal nuts F¹⁵ are screwed onto both the tubes E⁷ and E⁹ and grip between them 120 the positive or negative lead, as the case may be, from the electrical supply source. The tube E¹⁰ is formed, at its upper open end which faces the disc E¹⁴ with a valve seat V¹, with which a valve V³, having a 125

5 screwed stem V^4 and milled head V^5 , is adapted to cooperate, so as to control the mercury and mercury vapor issuing, when the tubular electrode is connected to the electrical supply source, from the tube E^{10} and impinging on the tungsten copper disc E^{14} . The stop-cocks H^3 , H^4 , are adapted to be used for charging the tubular electrode with mercury, liquids, chemicals or gases, 10 or for exhausting the electrode, or vapor space sealed chamber, or when working said space at atmospheric pressure. It will be understood that when an electrical current flows sideways, between and through the tubulous and channel electrodes, the mercury in the interior and exterior thereof is vaporized and passes in the case of the tubulous electrode through the valve V^1 , V^3 , and in the case of the channel electrode rises from 15 its upper open side and from its exterior surfaces, thus augmenting the supply of vapor from the mercury in the pockets D . Referring to Figures 5, 10 and 11, the lamp 20 comprises a single walled tube B^{10} which is closed at each end by an asbestos gasket C^{10} and otherwise as hereinbefore described and with electrodes E^{10} at both ends with corresponding terminals, the light passing through the sides of the single wall annular 25 mercury pockets D^{10} and the electrodes. These electrodes have the terminals E^{17} . P is the reflection lens, Q the wall of the lamp-house, and R the picture or object reflected back through the lens P onto the screen S . 30 The spiral lamp, or lamps, or any four of the double walled lamps, may replace the square battery of single walled lamps round the lens P (see Figures 10 and 11).

Figure 8 shows a spiral single walled tube 40 mercury lamp U , provided with a stop-cock trunnion T at the middle of its length, at right angles to the plane of the coil. The ends of the tube are attached to mercury pockets D^8 , which are secured to the two 45 ends of the tube. Stop-cocks and outside tubular terminals H^{18} are also provided for facilitating the charging of the spiral tube with mercury and fresh gas after the gas has been blown through in order to expel 50 the air and for adjusting the mercury level in the pockets D^8 .

An electrode such as herein described is provided in each mercury pocket and connected to the terminals.

55 The lamps illustrated in Figures 5 and 8 are particularly adapted for use when projecting an opaque object onto a screen. In Figures 10 and 11, for example, four single walled lamps B^{10} like Figure 5, are shown arranged square-wise around a circular lens P arranged in the wall Q of the lamp house, or any 4 double walled lamps like Figures 1, 6, 7, 9, 12 and 13 may be used for opaque reflection. The object R to be reflected is 60 arranged at the back of the lens P , while

the screen S is arranged in the front end thereof, the image of the object R being projected by the lens onto the screen S . When the spiral lamp U , in Figure 8, is used, the lens P^1 is arranged in the center 70 thereof, as shown.

In the saucer-shaped form of the lamp shown in Figure 6 the gaskets between the inner and outer shells are indicated at C^6 , the mercury pockets at D^6 and the electrodes 75 at E^{18} .

In the conical form of my lamp shown in Figure 7, the inner and outer shells are respectively indicated at A^7 , B^7 , the gaskets at C^7 , the mercury pockets at D^7 and the electrodes at E^{18} .

In Figure 9 I show a lamp of hemispherical form in which the inner and outer shells are respectively indicated at A^9 , B^9 , the gaskets at C^9 , the mercury pockets at D^9 , the electrodes at E^{20} , the space between the shells at X^1 and the space within the inner shell at Z^1 .

In the cylindrical form of my lamp shown in Figure 12, the inner and outer shells are 90 respectively indicated at A^{12} , B^{12} , the gaskets at C^{12} , the caps at J^{12} , the mercury pockets at D^{12} , the mercury at L^{12} , the inlets at G^{12} , the electrodes at E^{121} and the terminals at F^{121} . The space between the 95 shells is indicated at X^{12} and the space within the inner shell at Z^{12} .

Supplementing the brief description of Figure 13, the mercury pockets are indicated at D^{131} , the electrodes at E^{131} . In this 100 form of the invention the electrodes are indicated as tubular and one of them is shown provided with an inlet E^{122} and a stop-cock E^{123} .

The stop-cocks G , H are adapted to be 105 used for charging the electrode with mercury liquids, chemicals or gases, or for use when exhausting the electrode, or vacuum space or when working said space at atmospheric pressure. The detachable tube G^1 , 110 Figure 4, may be used for this purpose and is also adapted to be connected to the vertical limb of the elbow E^8 , Figure 15. It will be understood that the electrical current flowing through the channel and tubulous electrodes vaporizes the mercury in the interior thereof as well as that at the exterior, the mercury vapor from the interior of the tubulous electrode passing through the valve V^1 , V^3 , and vapor also 120 rising from the open top side of bottom horizontal electrode when lamp is vertical (either end up), and rising from the dipping sides of both electrodes when lamp is horizontal or inclined at an angle.

125 The double walled lamps may be attached by hinges to the gate W (see Figure 1) or side of a cinematograph projector.

It will be understood that the provision of an annular mercury pocket D , at both ends 130

of the lamp, ensures that the whole of the large intervening space X will be filled with the luminous mercury vapor, so that the light will be extremely brilliant. The 5 lamp may also be turned to any position about its axis owing to the annular pockets D and the electrodes E retaining the requisite mercury so that the lamp may be used while arranged vertically. If, for example, 10 the lamp is turned upwards to a vertical position, mercury vapor will still continue to be formed, because some of the mercury in one or other of the pockets will remain in the uppermost electrode E and also in the 15 chamber D, and hence the electrical connection between the top and bottom electrodes will not be broken.

The supply of vapor from said tubulous electrode can be readily regulated by means 20 of the valve V³. Said tubular and terminal electrode may also be used for supplying mercury to the interior of the lamp, or when working lamp at atmospheric pressure.

The trunnions with their stop-cocks H 25 and H¹ may be carried by gimbal rings so as to give a universal movement to each of the lamps.

Having thus described my invention, what I claim is:-

30 1. A mercury vapor lamp comprising, in combination, an outer shell and an inner shell arranged to form a hermetically sealed mercury vapor space therebetween, means at both ends of the outer shell, in communication with said space and adapted to contain mercury, and electrode means at each end of said lamp and in said mercury containing means for causing an electric circuit through the mercury and electrodes 40 sidewise at each end, and through said sealed space, whereby the mercury is vaporized and said space sealed with luminous mercury vapor.

45 2. A mercury vapor lamp as in claim 1 in which said outer shell is provided with conduits communicating with the mercury vapor space and each provided with a valve.

50 3. A mercury vapor lamp as in claim 1 in which the means at both ends of the outer shell for containing mercury is an annular pocket at each end of said shell and which communicates with the mercury vapor space.

55 4. A mercury vapor lamp as in claim 1 in which the means at both ends of the outer shell for containing mercury is an annular pocket at each end of said shell and which communicates with the mercury vapor space, and in which each electrode is also 60 annular in form and is arranged in one of the pockets.

65 5. A mercury vapor lamp as in claim 1 in which said outer shell is provided with conduits communicating with the mercury vapor space and each provided with a valve,

and in which a filler tube is provided for attachment to either of said conduits and is provided with a funnel and with controlling valves.

6. A mercury vapor lamp comprising, in 70 combination, an outer shell and an inner shell arranged in spaced relation, gaskets between the ends of said shells, forming end closures for said shells and coacting with said shells to form a hermetically sealed mercury vapor space therebetween, one of said shells having a mercury containing pocket at each end, and an electrode in each pocket, each electrode being secured to and carried by one of said gaskets.

7. A mercury vapor lamp comprising an outer shell and an inner shell arranged to form a mercury vapor space therebetween, one of said shells having a mercury containing pocket at each end communicating with 85 said space, a bushing extending through one end of the inner shell, an auxiliary lamp arranged in said inner shell and having a stem extending through said bushing, and an electrode in each of said pockets, said pockets and said electrodes being annular in form.

8. A mercury vapor lamp comprising an inner shell and an outer shell arranged in spaced relation to form a mercury vapor 95 space therebetween, said outer shell being provided with an annular mercury containing pocket in each end and communicating with said space, and a casing arranged in spaced relation to the outer shell and having its ends fitted on the outer walls of said 100 pockets, and an electrode in each of said pockets.

9. A mercury vapor lamp comprising an inner shell and an outer shell arranged in spaced relation, said outer shell having an 105 annular mercury containing pocket at each end, gaskets forming closures for the ends of said shells and coacting therewith to form a mercury vapor space between the shells, said gaskets bearing against the inner spaces 110 of the outer walls of said pockets, a casing arranged in spaced relation to the outer shell and having its ends arranged on the outer walls of said pockets, and caps on the ends of said casing, said shells and the outer sides 115 of said gaskets, and an electrode in each pocket, said electrodes being connected to and carried by said gaskets.

10. A mercury vapor lamp having an inner shell and an outer shell arranged to 120 form a mercury vapor space therebetween, one of said shells having a mercury containing pocket at each end, an electrode in each pocket, an auxiliary electric lamp in the inner shell and means to initially heat 125 the outer shell.

11. A mercury vapor lamp comprising inner and outer shells arranged in spaced relation to form a mercury vapor space therebetween and one of said shells having an 130

- annular pocket at each end, an annular electrode in each pocket, an auxiliary electric lamp in the inner shell and a lens at one end of the inner shell.
- 5 12. A mercury vapor lamp arranged to form a mercury vapor space therein and provided at each end with an annular mercury containing pocket and an annular electrode in each of said pockets.
- 10 13. A mercury vapor lamp arranged to form a mercury vapor space therein and pro- vided at each end with an annular mercury containing pocket and an electrode in each of said pockets, each of said electrodes being tubular and being provided with valve 15 inlets and also with an outlet for mercury vapor therefrom and with a valve to control said outlet.
- In testimony whereof I affix my signature.

JAMES NISBET.
